UNITED STATES PATENT OFFICE.

THOMAS E. MURRAY, OF BROOKLYN, NEW YORK.

CIRCULATION-TUBE FOR WATER-TUBE STEAM-BOILERS.

1,382,220.

Specification of Letters Patent. Patented June 21, 1921.

Application filed February 4, 1920. Serial No. 356,347.

To all whom it may concern:

Be it known that I, THOMAS E. MURRAY, a citizen of the United States, residing at Brooklyn, in the county of Kings and State of New York, have invented a certain new and useful Improvement in Circulation-Tubes for Water-Tube Steam-Boilers, of which the following is a specification.

The invention is a circulation tube for water tube steam boilers, having on its exterior a plurality of projections distributed at intervals over the length of said tube, the said projections being free except where attached to the tube and extending into the fire space when the tube is in place in the boiler. The object of the invention is to increase the heat conducting area of the tube.

In the accompanying drawing—

Figure 1 is a perspective view of my water tube.

Fig. 2 shows one flanged ring separately and in perspective.

Fig. 3 is a longitudinal diametral section of my tube.

Fig. 4 shows separately and in perspective one of the units which make up the complete flanged ring of Fig. 2.

Similar letters of reference indicate like parts.

A is the tube, upon which I place as many rings B, having double flanges C, D, as may be desired. Each ring with its flanges is formed of a number of curved sections

united by electrical welding at their ends. 35 In the drawing, I show each ring made up of four sections E, F, G, H, which are exactly alike and interchangeable, and may be struck up from the same dies. The rings are attached to the tube, preferably by electrical 40 welding.

The object of the device is to increase the heating surface of the tube. Said flanges, which project into the fire space, being directly heated by the surrounding gases, conduct said heat to the tube and so increase the capacity of a tube of given length for heating the water circulating therein. The flanges may be of any desired radial width, depending upon the amount of desired heat- 50 ing capacity.

I claim:

1. A circulation tube for water tube steam boilers, having on its periphery a plurality of rings; each ring having at both of its edges an outwardly turned flange formed by striking up the metal of the ring.

2. A circulation tube for water tube steam boilers, having on its periphery a plurality of double flanged rings; the said rings being 60 formed in arc-shaped sections electrically welded together at their ends.

In testimony whereof I have affixed my signature in presence of two witnesses.

THOMAS E. MURRAY.

Witnesses:

GERTRUDE T. PORTER,
MAY T. McGARRY.
